UNITED STATES PATENT OFFICE

1,939,009

ELECTRIC CIRCUIT

Fowler Hill, Brooklyn, N. Y.

Application February 21, 1931. Serial No. 517,572

1 Claim. (Cl. 173—346)

This invention relates to electric circuit closing devices and more particularly it pertains to time controlled electric switches.

It is one of the objects of the present invention to provide an electric switch of novel construction especially adapted for operative connection with a time piece of the alarm clock type.

It is another object of the invention so to construct a device of the aforementioned character that it may be capable of attachment to alarm clocks of ordinary construction.

It is still another object of the invention so to construct a device of the aforementioned character that the circuit will be opened in a quick manner by a snap action to eliminate arcing.

Still another object of the invention resides in the provision of novel means for operating the contact member to move it to circuit opening and closing position.

With the above and other objects in view, reference is to be had to the accompanying drawings forming a part of this application, in which:

Figure 1 is a rear perspective view of a conventional alarm clock showing a device constructed in accordance with the present invention attached thereto,

Figure 2 is a view in front elevation of the clock,

Figure 3 is a top plan view of a device constructed in accordance with the present invention,

Figure 4 is a view in elevation illustrating one side of the device,

Figure 5 is a similar view illustrating the opposite side of the device,

Figure 6 is a transverse sectional view taken on the line 6—6 of Figure 5,

Figure 7 is an enlarged longitudinal sectional view of the device,

Figure 8 is an enlarged longitudinal sectional view at right angles to Figure 7, and;

Figure 9 is a detail perspective view illustrating the circuit closing member.

In the present embodiment of the invention, the time controlling element is designated A, and is illustrated as a conventional form of alarm clock.

The device of the present invention is designated B, and the same is adapted to be secured in position upon an alarm clock by means of a right angular bracket or the like 10 which is secured to the alarm clock by means of clamping members 11 carried by one arm of the member 10, said arm being screw threaded to provide for

adjustment of the members 11 to clamping position. The other arm of the member 10 is slotted as at 12 to receive a bolt or the like carried by the member B and by means of which the member B may be adjustably clamped upon the arm 10 of the member by which it is carried. This construction is more clearly illustrated in Figure 8.

The device constructed in accordance with the present invention comprises a socket formed of hard rubber, bakelite, fibre or other suitable insulating material, and said socket preferably comprises two members 15 and 16 which are secured together by means of screws or the like 17 and 18 in a manner best illustrated in Figures 7 and 8. Mounted within the socket, there is the ordinary screw threaded socket shell 19 having the usual central contact member 20. Electricity conductors 21 and 22 extend from the shell and central contact respectively. As best illustrated in Figure 8, the conductor 21 terminates in a resilient arm or contact portion 23 spaced with respect to a similar member 24 to which a lead or the like 25 is connected by means of a screw 26. The conductor 22 is connected to a lead 27 by means of a screw 28 as best illustrated in Figure 7.

Mounted within the shell or socket, there is a contact completing element 30. This contact completing element is pivotally mounted as at 31 upon a bolt or the like 32 mounted in the sections 15 and 16 which form the socket, and this contact member has an arm or the like 33 which is adapted to engage between the contact members 23 and 24 heretofore mentioned to establish electrical connection between the conductor 21 and the lead 25 when the contact arm 30 is rocked about its pivotal point 31 in a manner to be hereinafter described.

Means is provided for rocking the contact member 30 about its pivotal point 31, and in the present embodiment of the invention, this means is illustrated as a cam 35 carried by a suitable shaft or the like 36. This shaft 36 extends entirely through the socket formed by the members 15 and 16 as best illustrated in Figure 3 of the drawings and upon one of its ends, said shaft carries a finger piece or the like 37 by means of which it may be rotated. Mounted upon the other end of the cam 36, there is a suitable clamp or the like 39 which is adapted to receive the alarm winding key of the alarm clock A. The alarm winding key is secured in position in the member 39 by means of a set screw or the like 40 and a spring 41.

The contact member 30 has an arm 45 corresponding to the arm 33 heretofore mentioned but extending in the opposite direction, and said cam 35 is adapted to engage either of these arms 32 or 45 dependent upon the rotation of the cam to operate the contact member 30 to cause the same to either complete or break the circuit of the electrical conductor 21 and the lead 25.

Means is provided to limit the rotating movement of the cam 35, and in the present embodiment of the invention, this means comprises a stop 46 (see Figure 7) which as best illustrated in Figure 6 of the drawings comprises a bolt or the like 47 cut out as at 48 and spring pressed by means of a spring 49 to maintain that portion designated 50 in the path of movement of the cam 35 so that when the cam 35 turns, it will engage the stop 46 and prevent further movement thereof.

Means is provided to give a quick or snap action to the contact member 30 in its movement into and out of engagement with the members 23 and 24, and this means is best illustrated in Figure 9. The stem 55 of the contact member 30 is pivotally connected to a member 56 carried by a bolt or the like 57 which is mounted upon a suitable pin or similar member 58. The member 56 is slidably mounted upon the bolt 57, and during its sliding movement, it serves to place a spring or the like 59 under compression. Immediately the pivot connection between the stem 55 of the contact member 30 with the member 56 passes dead center, the spring which is placed under compression serves to throw the contact member 30 with a sudden impulse and cause rapid engagement and disengagement with the contact members 23 and 24 and thus prevent arcing during the operation of making or breaking the circuit.

The device operates in the following manner: It having been attached to the winding key of an alarm clock in the manner heretofore described, it will be obvious that when the alarm clock is set off at any given time, the shaft 36 will be rotated by the unwinding of the winding key and will operate the cam 35 to engage the arm 33 of the contact member 30 and move it to

circuit closing position. Before this action takes place, the several parts are in the position in which they are illustrated in dot and dash lines in Figure 7, and during movement of the cam to contact operating position, in which position it is shown in full lines in said Figure 7, the spring 59 is placed under compression and immediately the pivotal point between the contact member 30 and the member 56 passes dead center, the contact member 30 will be snapped either into or out of engagement with the contacts 23 and 24 to complete the circuit between the conductor 21 and the lead 25 as heretofore described. If the cam be rotated in the opposite direction by means of the finger piece 37, the alarm train or its spring will be again placed under tension, and the cam will be simultaneously moved to disengage the contact member 30 with the contacts 23 and 24 and thereby break the electrical circuit between the conductor 21 and the lead 25.

From the foregoing it will be apparent that the present invention provides a new and improved device by means of which an electrical circuit may be established at any predetermined time, which electrical circuit may be employed for operating an alarm, radio, furnace or other electrical appliance as desired.

While the invention has been herein illustrated in a preferred form, it is to be understood that the invention is not to be limited to the specific construction herein shown, and that it may be practiced in other forms without departing from the spirit thereof.

Having thus described the invention, what is claimed as new, and what it is desired to secure by Letters Patent of the United States, is:

In a switch, a socket member having fixed contacts, a switch element pivoted within said socket member and having pairs of laterally spaced outwardly curved arms and bridge elements joining the arms of each pair, spring means to urge said arms into engagement with said fixed contacts, a cam having a rounded lobe positioned for engaging the bridge elements, and means supporting the cam for movement between said bridge elements.

FOWLER HILL.
